UNITED STATES PATENT OFFICE

GEORGE M. SOULE, OF CLEVELAND, OHIO, ASSIGNOR TO THE PLOW-MATE INC., OF CLEVELAND, OHIO, A CORPORATION OF OHIO

SOIL PULVERIZER

Application filed November 16, 1927. Serial No. 233,542.

This invention relates to furrow slice pulverizers for use in connection with breaking plows. An object is to provide a simple and economically manufactured device for supporting a set of pulverizing blades in the desired position with reference to the mold-board of the plow. A further object is to provide an improved arm for supporting a set of blades from the plow beam, free from the mold-board, which arm may be easily and quickly adjusted to operate with any size and type of breaking plow. Further objects include the provision of an improved and simplified connection between a holder for a set of blades and a rigid support, which connection will allow substantially universal yielding movement between the blades and support, but which will normally hold the blades in a definite position and return them to this position after the yielding takes place.

Further objects and features of the invention will become apparent from the following description relating to the accompanying drawings wherein is shown the preferred form. The essential novel characteristics will be summarized in the claims.

In the drawings, Fig. 1 is a rear elevation of a plow with the improved device attached in operating position; Fig. 2 is a longitudinal cross-sectional view of the arm taken generally along the line 2-2 on Fig. 1; Fig. 3 is a rear end elevation of the free end of the arm showing particularly the yielding connection to allow sidewise movement of the blades in clearing an obstruction. This figure shows the parts adjusted for use with a left hand plow. Fig. 4 is a detail cross-sectional view showing the yielding device in entirety; Figs. 5 and 6 are detail cross-sectional views as indicated by the lines 5-5 and 6-6 on Fig. 2; Fig. 7 is a detail view showing a device to prevent slippage of the normally rigid arm section; Fig. 8 is a cross-sectional view of the arm attaching parts shown in Fig. 2, but in a different relation to the plow beam, and Fig. 9 is a cross-sectional detail view of a suitable blade clamping device as indicated by the line 9-9 on Fig. 3.

The major parts of the embodiment illustrated comprise: A longitudinally fixed arm

section 1; a longitudinally adjustable section 2; an arcuately adjustable plate 3 mounted on the free end of the section 2 and positionable about a bolt 4 as a center; a blade holding member 5 yieldingly mounted on the plate 3; blades, three in number as shown, designated 6, 7 and 8, and springs 9 and 10. A well known type of plow is illustrated to bring out the relationship of the device thereto, the plow beam being designated A, the mold board C and the land-side B. It is to be understood that wherever the above plow parts, such as beam and mold board, are mentioned in the following specification and claims, these terms are not intended to limit the scope of my invention, but to explain the use thereof in connection with the most common form of plow. For example, any rigid frame portion of the plow is to be considered the equivalent of the beam, and any soil turning or moving element the equivalent of a mold board.

The invention contemplates the provision of a universally adaptable device, namely for right or left hand plows of various makes, types and sizes, hence considerable adjustment is necessarily provided for. Mold-boards vary in length, distance of the delivery edge from the beam, height of the delivery edge from the furrow channel bottom, etc., and beams vary in shape and as to all dimensions. Further, it is highly desirable to position the blades as a whole in a peculiar relation to the furrow slice as the same leaves the mold-board so that each blade will operate to the best advantage in slicing and pulverizing the soil. Considerable difficulty has been encountered in attaining the desired peculiar relationships, particularly when the device has to accommodate right and left hand plows indiscriminately. The manner in which the invention meets the various conditions as above outlined, will be presently shown.

The arm section 1 may be attached at any point on the beam and on any face depending on which mode of attachment will bring the blades with their shank portions just clear of the delivery edge of the mold-board and in the most effective position to cut into

the furrow slice just as it leaves the board and while still moving. As shown the section 1 rests on an adapter plate 15 which may be slightly dished on both major surfaces to better fit the beam and which is somewhat wedge-shaped in order that it may be reversed end for end if necessary to vary the inclination of the whole arm in a substantially horizontal plane. If desired, both 10 sides of the plate may be serrated or roughened for better gripping effect on the beam, and to hold it against slipping out of place due to the wedge shape. The plate is slotted at 16 to receive clamping bolts 17 and 18, the 15 former being an L bolt passing along two adjacent sides of the beam and the latter being an eye bolt passing along one side only. One end of the bolt 17 passes through the eye and carries a nut 17a. The other end of the 20 bolt 17 and the end of 18 opposite the eye pass through the plate 15 and the arm section 1 and carry nuts 17-b and 18a respectively.

In Fig. 8 the arm is shown attached by means of the same bolts but at the side of the 25 beam instead of at the edge. The relations will be easily understood from inspection. It is to be understood that the arrangement is adapted for securing the arm to the beam along any face and in any position along the 30 downwardly extending portion of the beam.

The arm section 1 is adapted to be made from pressed steel for the sake of lightness of construction and for strength, as are the parts 2, 3 and 5. The section 1 comprises a clamp portion 20 including clamping flanges 21 adapted to receive a series of bolts 22, the portion 20 embracing the shank 30 of the section 2. Intermediately of its ends the section 1 is formed into a flattened tapered tubular shape at 23 including inturned flanges 24 (Fig. 5), forming in effect, together with an elongated aperture 25, a slot for embracing the bolt 17. The extreme end of the section 1 has an arcuate slot formed by flanges 26 and 27 for embracing the bolt 18. The purpose of the latter slot is to provide for adjustment of the entire arm in a substantially vertical plane in order to raise or lower the blade mounting as required because, as above mentioned, the 50 mold-board varies in distance from the furrow channel bottom, and because it is sometimes impossible to arbitrarily choose the point at which the arm is to attach to the beam. If necessary, because of heavy strain, 55 the edges of the flanges 26 and 27 may be notched as at 26a and 27a (Fig. 7) to receive projections 28 on a washer beneath the nut 18a to effectively prevent slippage between the bolt 18 and the section 1 at the slot. 60 When the arm is properly adjusted and the nuts tightened down on the bolts 17 and 18 the arm section 1 will be very rigid and not likely to slip or move in any direction. The inclination of the surface engaged by the nut 17b will serve to force the bolt 17 toward the

beam for more tightly clamping it between the two bolts.

The telescoping arrangement of the arm sections 1 and 2 provides for elongating or shortening the effective reach of the arm, and as shown, the portion 30 of the section 2 is in general cylindrical, so that it may be turned to change the inclination of the blades as a whole. This is important since the uppermost blade should be disposed forwardly of 75 the lowermost blade in the direction of plowing to better conform to the condition of the furrow slice as it leaves the mold-board. In adapting the device for use with a left-hand plow the blade mounting is turned considerably from the position it requires for right hand plow use. Preferably the adjacent surfaces of the telescoping portions of the arm sections 1 and 2 are partially longitudinally 80 corrugated as shown at 33 and 34 to aid the 85 clamp in preventing relative rotational movement between the sections. The section 2 may consist simply of a tube flattened out at 31 to receive the plate 3 and having its extreme end offset as at 32 forwardly of the 90 spring 9 to accommodate the shape of the plate 3 at this point.

It is obviously desirable to provide for yielding movement of the blades with reference to the arm since, in plowing, obstructions are often encountered which cannot be cut by the blades or readily shoved aside. The arrangement illustrated permits the blades to yield flatwise for clearing small obstructions or any obstruction encountered with a glancing blow, and to yield edgewise for larger and more refractory obstructions. The mounting member 5 pivots about the bolt 4 as a center, and the flatwise yielding of the blades is permitted by reason of the tension spring 10. Direct or edgewise yielding is permitted by reason of the compression spring 9, which surrounds the bolt 4 and reacts at one end against an adjustable nut 4a on the bolt, and at the other against the member 5. To guide 100 the member 5 back into place, after the direct yielding, the member 5 and plate 3 have complementary depressed portions 35 and 36, adjacent the bolt 4. The depressions determine the pivotal center of the member 5; hence the 105 opening in the member 5 for the bolt 4 may be large enough to allow more or less universal movement between the arm and blade mounting. As shown one anchorage for the spring 10 comprises a rivet 45 in an ear 46 on the 110 member 5. The head of the rivet rests as shown directly on the plate 3. In moving against the force of the spring 9 the mounting cant about the rivet head as a fulcrum 115 (see Fig. 4). The opening 37 in the member 120 5 is preferably elongated in the direction of the blades to allow the canting movement, while laterally guiding the mounting along the bolt to prevent excessive play.

While it is highly desirable to allow flat- 125

- wise yielding movement of the blades, as by rotation about the axis of the bolt 4, it is not desirable to allow this movement, at least to any appreciable extent, in a direction which would allow any of the blades to dig down into dead soil. This will be appreciated with reference to Fig. 1. Consequently provision is made to prevent rotation of the mounting in one direction in either right or left hand plow use. Referring to Fig. 3 it will be noted that the ear 46 on the member 5 is prevented from moving counter-clockwise by reason of one of two abutments formed by short flanges 48, on the laterally opposite edges of the plate 3. The anchorage for the spring 10 at the plate 3 comprises an eye bolt 50 which may be moved from one opening as at 51 to another as at 53 along a flange 52 of the plate 3. The eye bolt nut has a blunt wedge face engaging a depression 54 in the flange, the nut being for adjusting the tension of the spring, and the wedge and depression cooperating to maintain the adjustment. After the spring is properly positioned and tensioned, the plate 3 may be swung up or down and clamped in place by reason of a bolt and slot connection at 55—56 between the plate and arm section 2. It will be noted that for right-hand plow use (Figs. 1 and 4) one end of the slot is occupied by the bolt and the spring is anchored at 51 while for left-hand plow use (Fig. 3) the other end of the slot is occupied by the bolt and the spring is anchored at 53. This is to direct the blades downwardly about as shown in Fig. 1 in either case, and to render only one of the two abutments 48 effective at a time.
- The preferred clamping device for the blades comprises a sector shaped extension 60 of the mounting member 5, suitably channeled as at 61 and flanged at 62, for receiving the forward edges of the blade shanks, and a separate clamp member 65 channeled as at 66 for the rear edges of the blades. The blade clamping members may be drawn together on the blades as by bolts 67.
- I claim:—
1. In a device of the class described, a rigid arm section adapted to be secured to a plow, a longitudinally adjustable arm section in telescoping relation to the rigid section, a plurality of elongated blades one above the other and mounted on the second mentioned section, the longitudinally adjustable section being turnable with reference to the rigid section to position the uppermost blade forwardly of the adjacent blades in the direction of plowing.
  2. In a breaking plow, a plurality of blades positioned adjacent the delivery end of the mold-board, a pressed metal plate having a rounded depression, means carried by the plow and arranged to adjustably support the plate, a blade holding member having a rounded portion substantially complemen-
- tary to the depression in the plate, thus forming a ball and socket joint, there being means tending to hold the plate and said member together, and resilient means interposed between the plate and said member to yielding- 70
